UNITED STATES PATENT OFFICE.

JAMES M. JAY, OF NEW YORK, N. Y.

APPARATUS FOR STRETCHING CARPETS.

SPECIFICATION forming part of Letters Patent No. 226,917, dated April 27, 1880.

Application filed October 3, 1879.

To all whom it may concern:

Be it known that I, JAMES M. JAY, of the city, county, and State of New York, have invented certain Improvements in Apparatus 5 for Stretching Carpets, of which the following is a specification, reference being had to the drawings, in which—

Figure 1 is a side view of my improvement in its contracted or shortest form when in use. 10 Fig. 2 is a similar view, showing my improvement in its extended form; Fig. 3, a face view of the tooth-plate; Fig. 4, a side view of a section of the apparatus, showing the mechanism whereby the sections of my apparatus are held 15 in place, and Fig. 5 a top view of said mechanism, the same being a thumb spring pivot.

My invention consists in the construction of a rod or bar in sections, so arranged and connected that it can be extended or shortened as desired, in combination with a plate-hook, the whole being easily folded up ready for carrying, or, when in use, adaptable to any length of room in which it is desired to be used. 25

In the drawings, A represents the bars or rods, formed in four pieces, a a' a^2 a^3 . On the end of the bar a is fastened the plate-hook B, which has the teeth b, which teeth engage with and hold in the carpet. The bar a is fastened 30 to and slides on the bar a' by means of devices shown in Figs. 4 and 5, which devices consist of a band or ribbon, c, with a thumb head or piece, d, attached to the piece a . Under said thumb-piece is placed the spring g, which serves 35 to press the said thumb-piece d, and with it the band c, which are formed in one piece, onto the piece or section a^2 , the upper side of said band resting and working in the notch or slot. Thus when the thumb-piece is pressed down the 40 lower side of band c is thrown out of contact with the rod a , allowing the rod to be moved longitudinally. When the pressure on the thumb-piece is removed it is thrown upward by the spring g, and the lower side of the band 45 c is made to impinge against the face of the bar a and prevent its longitudinal movement.

The band or ribbon h holds the sectional pieces a a' together in position and prevents lateral motion.

The bars a' and a^2 are hinged together at 50 their ends, the hinge allowing downward movement. The rods a^2 and a^3 are held in position and lateral motion prevented in like manner as a' and a .

In the operation of my improved stretcher 55 the bars are stretched out or extended to the desired length, the plate-hook by its teeth engaging in the carpet, and the end of the opposite bar, a^3 , either resting against the side-board of the room or against a flat piece, so it 60 will not slip or move longitudinally. By pressure applied at D—the leverage-point—the end having the plate-hook and teeth is pushed out, taking with it the carpet, until the carpet is stretched the desired distance or to the nail- 65 line, where it is secured by tacks. The end of the bar a^3 remains unmoved. By regulating the extension of the bars a a' a^2 a^3 the length may be such as to push the carpet to the nailing-point, when and at the same time 70 the rods are all in one straight line in the same plane, and the hinged point pressed to the floor, in which case the carpet is held till secured, and thus one person alone can stretch and nail the carpet. 75

When through using the stretcher it is folded together, section on section, one over the other, first by sliding, then folding, and the whole easily carried from place to place.

What I claim, and desire to secure by Letters Patent, is—

A carpet-stretcher composed of the sectional rods or bars a a' a^2 a^3 , held together, as shown, and whose longitudinal motion is regulated by the band c, having the thumb-piece d and spring 85 g, said bars being hinged together, as shown, in combination with the hook-plate B, having teeth b, all as specified and described.

JAMES M. JAY.
